UNITED STATES PATENT OFFICE.

CLARENCE B. DES JARDINS, OF TOLEDO, OHIO, ASSIGNOR TO INDUSTRIAL RESEARCH CORPORATION, OF TOLEDO, OHIO, A CORPORATION OF DELAWARE.

LIQUID-FEEDING DEVICE.

1,364,486.

Specification of Letters Patent. Patented Jan. 4, 1921.

Application filed June 15, 1918. Serial No. 240,144.

To all whom it may concern:

Be it known that I, CLARENCE B. DES JARDINS, a citizen of the United States, residing at Toledo, in the county of Lucas and State of Ohio, have invented certain new and useful Improvements in Liquid-Feeding Devices, of which I declare the following to be a full, clear, and exact description.

10 The present invention relates to a liquid feeding device and has for its object to provide more particularly, improved means for feeding gasolene or other liquid fuel from a relatively low level such as the supply tank at the rear end of an automobile, to a plurality of feed tanks or receptacles elevated with respect to said supply tank and arranged to provide a continuous flow of fuel to the carburetor of the engine or other liquid receiving vessel, in order that a constant level may be maintained therein, said fuel being forced into the feed tanks by any suitable means, but preferably by suction produced in the intake manifold of the engine which, in the preferred embodiment of the invention, is connected with the supply tank through said feed tanks.

15 A further object of the invention is to provide a plurality of vacuum controlled feed tanks, preferably two, which are elevated with respect to a liquid supply source and connected with an aspirator or suction producing apparatus and provided with means for alternately placing said tanks in communication with the aspirator for the purpose of affording a continuous feed or supply of fuel to a low level receiving vessel such as the carburetor of an internal combustion engine.

20 A still further object of the invention is to provide an improved valve arrangement for alternately opening and closing the air inlet and suction controlled passageways communicating with two vacuum fuel feed tanks to and from which liquid is alternately fed and discharged.

25 Further objects, and objects relating to economies of manufacture and details of construction, will definitely appear from the detailed description to follow:

I accomplish the objects of my invention by the devices and means described in the following specification. My invention is

clearly defined and pointed out in the appended claims.

55

A structure constituting a preferred embodiment of my invention is illustrated in the accompanying drawings, forming a part of this specification, in which:

Figure I is a view in elevation and partly in section, showing the manner of connecting the vacuum feed tanks with the intake manifold of the engine and with the carburetor and fuel supply tank.

Fig. II is a fragmentary, top plan view 65 of the vacuum feed tanks and parts controlling the supply of liquid thereto.

Fig. III is a sectional elevation through the feed tanks taken on line III—III of Fig. II.

70

Fig. IV is a fragmentary sectional elevation of the tanks taken on line IV—IV of Fig. II.

75

Fig. V is a sectional plan of the suction and air controlling valves taken on line V—V of Fig. III.

Fig. VI is a sectional elevation taken on the line VI—VI of Fig. II.

Fig. VII is a fragmentary, sectional elevation of the upper portion of one of the feed tanks with the float controlled valve operating mechanism shown in its uppermost position, and

Fig. VIII is a fragmentary, sectional elevation of the tank at the right of Fig. III 85 showing the suction conduit leading thereto closed by a supplemental float actuated valve.

Referring to the drawings, 1 represents an internal combustion engine provided 90 with a suitable carburetor 2, and an intake manifold 3 forming the aspirator or suction producing apparatus for lifting the liquid fuel from the main low level tank or liquid supply source 4 through the conduit 95 5 to the receptacle 6 divided by the partition 7 to form the independent vacuum feed tanks having the liquid receiving chambers 8 and 9 from which the liquid is alternately fed by gravity to the carburetor through the conduit 10, said tanks or chambers being connected with the intake manifold of the engine by means of the suction conduit 11, as shown in Fig. I.

The fuel supply conduit 5 is provided 105 with the branch pipes 13 and 14 connected

preferably with the elbows 16 and 17 from which extend the connections 18 and 19 projecting through the cover 20 of the tanks into the chambers 8 and 9, respectively, 5 which are secured upon the cover by means of the inner and outer locking nuts 21 and 22, as clearly shown in Fig. III.

The suction conduit 11 is connected with the threaded portion 24 of the valve casing 10 25 from which extends through the cover 20 and into the liquid receiving chambers 8 and 9, the threaded connections 26 and 27, respectively, each being provided with a suction passageway leading to the valve chamber 15 in which is mounted the valve 28 having the recess 29 adapted to alternately establish communication between said chambers and said suction conduit, whereby the liquid is fed first into one of the feed tanks and then 20 into the other.

The valve casing and connections 26 and 27 are preferably integral and the portions of the casing having the horizontal passageways are preferably bored through from the 25 ends of the valve chamber for the sake of economy in manufacture and are then plugged by means of the screws 30, as shown in Fig. III. The connections 26 and 27 are preferably secured in position upon the cover 30 20 by means of inner and outer lock nuts 31 which are threaded upon said connections on the opposite sides of the cover.

The air inlet passageways for alternately venting each of the feed tanks when the 35 other is in communication with the suction producing apparatus are formed through the valve casing 32 in which is mounted the valve 33 provided with the oppositely positioned recesses 34 and 35, as shown in 40 Fig. IV.

The valve casing 32 is supported preferably by the elbows 36 and short nipples or connections 37 and 38, the former extending into the feed chamber 8 and the latter into the feed chamber 9 and each being preferably threaded to receive the locking nuts 39 on the opposite sides of the cover 20.

The air inlet passageway 40 leading to the chamber 8 is adapted to be closed by the 50 valve 33 when the valve 28 is in position to open the suction passageway leading to said chamber, but at the same time, the air inlet passageway 41 leading to the chamber 9 is open. This operation, of course, is reversed 55 when the valve 28 is in position to open the suction passageway leading to the chamber 9.

The air inlet passageways 40 and 41 are adapted to communicate with the vertically 60 disposed passageway 42 through the recesses 34 and 35 respectively of the valve 33 when the latter is moved to its extreme positions of travel in a manner which will presently be described.

65 The valves 28 and 33 preferably comprise

the opposite ends of a cylinder which extend through the spaced valve casings 25 and 32 to receive the washers 43 and nuts 44, as shown in Fig. V. I preferably make the valve casings in separate parts rather than 70 integral and the valves in one piece in preference to separating them, but do not wish to limit the same to this particular form of construction.

The valve or valves are actuated by the 75 lever arm 45 extending between the valve casings from the central or connecting portion of the valves, as shown in Figs. II and V.

The arm is actuated by the float 46 in the 80 tank 8 when said float reaches predetermined points in its up and down movement within the tank, as will hereinafter appear.

The float is provided with a centrally disposed sleeve 47 through which extends the 85 guide post 48, the upper end of which is reduced and projected through an opening in the cover 20 and adapted to receive the nut 49, between the inner face of which and the outer end of the reduced portion of the 90 post is provided the packing 50, the lower end of said post being preferably projected through the bottom wall of the tank, as shown in Fig. III.

The post at its upper end is provided with 95 a longitudinally disposed bore 51 into which extends the valve lever actuating rod 52, said rod being also projected through the nut 49 and packing 50 and provided with a hooked end 53 engaging the arm or lever 45 100 within the slot 54 at its outer end, as shown in Figs. III and VI.

A transverse slot 55 in the post 48 intersects the bore 51 and registers with the oppositely positioned slots 56 in the float sleeve 105 47. Extended through said slots and the bottom of the rod 52 is a pin 57 which is freely movable within the slots. The opposite ends of the pin, in the preferred embodiment of the invention, project through 110 the elongated slots 58 formed in the enlarged ends 59 of the arms 60 which are pivoted at 61 upon the post 62 extending downwardly from the cover 20, as shown in Fig. III.

Connected with the outer ends of the pin 115 57 are the coil springs 63 extending longitudinally of the arms 60, said springs being anchored to the clips or brackets 64 upon the side wall of the tank, as shown in Fig. III.

The sleeve 47 is provided with the upper 120 and lower projections 65 and 65' respectively, which are preferably in the form of annular rings and which, when the float 46 is moved up and down by the rise and fall of liquid in the tank, engage the enlarged 125 ends 59 of the arms 60 to move the latter upon their pivots, whereby when the springs 63 are carried past said pivotal points, either in the up or down movement of the float, the valve operating rod 52 will 130

be actuated by the tripping action of the springs thereby quickly operating the air inlet and suction controlling valves for alternately venting and placing the feed tanks in communication with the intake manifold of the engine or whatever form of aspirator it is desired to use.

The liquid is preferably discharged from the feed chamber 8 through the passageway 66 in the bottom of the post 47, the latter being threaded exteriorly of the tank to receive the elbow 66' connected with the conduit 10 leading to the carburetor by means of the short pipe 67 and T-head 68, as shown in Fig. III.

Liquid from the feed chamber 9 is discharged into the conduit 10 through the nipple 69, elbow 70, short pipe 71 and T-head 68, said nipple being threaded to receive the nut 72 on the inner face of the tank and the elbow 70 on the outer face, as shown in Fig. III. The elbows 66' and 70 are each provided with a valve seat 73 and a ball valve 74 for preventing the flow of liquid upwardly into the tanks 8 and 9, thus avoiding the mere transfer of liquid from the tank which is under atmospheric pressure to the tank which is under suction.

The elbows containing the ball valves are adapted to be drained by removing the thumb screws 75, shown in Fig. III.

In order to prevent the possible withdrawal by suction of the liquid from the feed chamber 9 through the connection 27 of the valve casing 25 in cases where the chamber 9 might be filled faster than the chamber 8 is emptied, I provide the valve 76 adapted to be moved into engagement with the seat 77 on the lower end of said connection 27 by movement of the float 78 on the guide post 79 when the liquid in the chamber has reached a predetermined height. By this means, the supply of fuel to said chamber at each filling operation is limited to a predetermined amount, which is approximately the amount fed to the chamber 8 at the time the suction passageway leading thereto is closed by the valve 28.

I am aware that the particular embodiment of my invention, which I have here shown and described, is susceptible of considerable variation without departing from the spirit thereof, and, therefore, I desire to claim the same broadly, as well as specifically, as indicated by the appended claims.

Having thus described my invention, what I claim as new and desire to secure by Letters Patent, is:

1. In a liquid feeding device, the combination with a liquid supply source and a suction producing apparatus, of a liquid receiving tank connected with said supply source, a second tank connected with said supply source, and means for alternately placing said tanks in communication with

said suction apparatus, said means being controlled by the rise and fall of liquid in one only of said tanks.

2. In a liquid feeding device, the combination with a liquid supply source and a suction producing apparatus, of a liquid receiving tank connected with said supply source, a second tank connected with said supply source, means for alternately placing said tanks in communication with said suction apparatus, and a float in one only of said tanks for controlling said means.

3. In a liquid feeding device, the combination with a liquid supply source and a suction producing apparatus, of a liquid receiving tank connected with said supply source, a second tank connected with said supply source, a conduit leading from said suction apparatus having passageways communicating with each of said tanks, and a single float controlled valve for alternately opening and closing said passageways.

4. In a liquid feeding device, the combination with a liquid supply source and a suction producing apparatus, of a liquid receiving tank connected with said supply source, a second tank connected with said supply source, connections between said suction apparatus and said tanks having passageways leading to each of the latter, and means controlled by a float in one only of said tanks for alternately opening and closing said passageways.

5. In a liquid feeding device, the combination with a liquid supply source and a suction producing apparatus, of a liquid receiving tank connected with said supply source, a conduit leading from said suction apparatus having passageways communicating with each of said tanks, means controlled by a float in one only of said tanks for alternately opening and closing said passageways, outlet conduits leading from said tanks, and means for preventing the return of liquid through said conduits to said tanks.

6. In a liquid feeding device, the combination with a liquid supply source and a suction producing apparatus, of a liquid receiving tank connected with said supply source, a second tank connected with said supply source, means for alternately placing said tanks in communication with said suction apparatus, and additional means for interrupting communication with one of said tanks when the liquid therein reaches a predetermined point.

7. In a liquid feeding device, the combination with a liquid supply source and a suction producing apparatus, of a liquid receiving tank connected with said supply source, a second tank connected with said supply source, means for alternately placing said tanks in communication with said suction apparatus, additional means for preventing suction in one of said tanks when

- the liquid therein reaches a predetermined point, conduits leading from said tanks, and means for preventing the return of the liquid through said conduits to said tanks.
5. In a liquid feeding device, the combination with a liquid supply source and a suction producing apparatus, of a liquid receiving tank connected with said supply source, a second tank connected with said supply source, means for alternately placing said tanks in communication with said suction apparatus, a valve in addition to said last mentioned means for preventing suction in one of said tanks, and liquid controlled 10 means for actuating said valve.
9. In a liquid feeding device, the combination with a liquid supply source and a suction producing apparatus, of a pair of liquid receiving tanks connected with said supply 20 source, means for alternately venting and placing said tanks in communication with said suction apparatus, and additional means for interrupting communication with one of said tanks when the liquid therein reaches a predetermined height.
10. In a liquid feeding device, the combination with a liquid supply source and a suction producing apparatus, of a liquid receiving tank connected with said supply source, a second tank connected with said supply source, means for alternately venting and placing said tanks in communication with said suction apparatus, additional means for interrupting communication between said suction apparatus and one of said tanks when the liquid therein reaches a predetermined height, outlet conduits leading from said tanks, and means for preventing the return of the liquid therethrough.
11. In a liquid feeding device, the combination with a liquid supply source and the intake manifold of an internal combustion engine, of a liquid receiving tank connected with said supply source, a second tank connected with said supply source, conduits between said tanks and said manifold, and means controlled by the rise and fall of liquid in one only of said tanks for alternately opening and closing said conduits.
12. In a liquid feeding device, the combination with a liquid supply source and the intake manifold of an internal combustion engine, of a liquid receiving tank connected with said supply source, a second tank connected with said supply source, means for alternately venting and placing said tanks in communication with said manifold, means actuated by the rise and fall of liquid in one of said tanks for controlling said last mentioned means, and additional means in the other tank for preventing suction therein when the liquid in the same reaches a predetermined height.
13. In a liquid feeding device, the com-

bination with the intake manifold and the carburetor of an internal combustion engine, of a fuel supply source for the latter, a fuel receiving tank connected with said supply source, a second tank connected with said supply source, a conduit between said manifold and said tanks having passageways leading to the latter, a valve movable to alternately open and close said passageways, and a float in one of said tanks operatively connected with said valve.

14. In a liquid feeding device, the combination with the intake manifold and the carburetor of an internal combustion engine, of a fuel supply source for the latter, a fuel receiving tank connected with said supply source, a second tank connected with said supply source, a conduit between said manifold and said tanks, having passageways leading to the latter, a valve movable to alternately open and close said passageways, a float in the first mentioned tank operatively connected with said valve, and additional means controlled by the rise and fall of liquid in the other tank for preventing suction therein.

15. In a liquid feeding device, the combination with the intake manifold and the carburetor of an internal combustion engine, of a fuel supply source for the latter, a fuel receiving tank connected with said supply source, a second tank connected with said supply source, a conduit between said manifold and said tanks having passageways leading to the latter, a valve movable to alternately open and close said passageways, a float in the first mentioned tank operatively connected with said valve, an additional valve for closing the passageway leading to the second mentioned tank, and a float in the latter for actuating said last named valve.

16. In a liquid feeding device, the combination with a liquid supply source and an aspirator, of a liquid receiving tank connected with said supply source, a second tank connected with said supply source, a valve casing having passageways leading to each of said tanks, a conduit connected with said casing and said aspirator, a valve in said casing movable in opposite directions to alternately open and close said passageways, a float in one of said tanks operatively connected with said valve, and outlet conduits leading from said tanks.

17. In a liquid feeding device, the combination with a liquid supply source and an aspirator, of a liquid receiving tank connected with said supply source, a second tank connected with said supply source, a valve casing having passageways leading to each of said tanks, a conduit connecting said casing with said aspirator, a valve in said casing movable in opposite directions to al-

- ternately open and close said passageways, a float in one of said tanks operatively connected with said valve, an additional valve in the other tank adapted to open and close 5 the passageway leading thereto, a float for actuating said latter valve and outlet conduits leading from said tanks.
18. In a liquid feeding device, the combination with a liquid supply source and an 10 aspirator, of a liquid receiving tank connected with said supply source, a second tank connected with said supply source, a valve casing having passageways leading to each of said tanks, a conduit connecting said casing with said aspirator, a valve in said casing movable in opposite directions to alternately open and close said passageways, a float in one of said tanks operatively connected with said valve, an additional valve 15 in the other tank adapted to open and close the passageway leading thereto, means controlled by the flow of liquid through said last mentioned tank for actuating said last named valve, each of said tanks being provided with an outlet passageway and means 20 for closing the same when suction is produced in the tanks.
19. In a liquid feeding device, the combination with a liquid supply source and an 25 aspirator, of a liquid receiving tank connected with said supply source, a second tank connected with said supply source, a valve casing having passageways leading to each of said tanks, a conduit connecting said 30 casing and said aspirator, a valve in said casing adapted to alternately open and close said passageways, said tanks being provided each with an air inlet passageway, a second valve in said casing adapted to alternately open and close said air inlet passageways, the air inlet passageway of each tank being closed when the aspirator is in communication therewith and means for actuating 35 said valves.
20. In a liquid feeding device, the combination with a liquid supply source and an aspirator, of a liquid receiving tank connected with said supply source, a second tank connected with said supply source, each of 40 said tanks being provided with an air inlet passageway and a suction passageway leading to said aspirator, means for alternately opening and closing the air inlet and suction passageways leading to each of said tanks, a 45 float in one only of said tanks for actuating said means, and an additional float actuated valve for opening and closing the suction passageway leading to the other of said tanks.
21. In a liquid feeding device, the combination with a liquid supply source and an aspirator, of a liquid receiving tank connected with said supply source, a second tank connected with said supply source, each 50 of said tanks being provided with an air inlet passageway and a suction passageway leading to said aspirator, an oscillatory valve for alternately opening and closing the air inlet and suction passageways leading to each 55 of said tanks, a float in one of said tanks for actuating said valve, a float in the other of said tanks, and a valve actuated thereby for closing the suction passageway leading to said last mentioned tank when the liquid 60 therein reaches a predetermined point.
22. In a liquid feeding device, the combination with a liquid supply source and an aspirator, of a liquid receiving tank connected with said supply source, a second tank connected with said supply source, spaced 65 valve casings, one of which is provided with an air inlet passageway leading to each of said tanks, and the other connected with said aspirator and provided with suction 70 passageways leading to each of said tanks, valves for each of said casings, a lever connected with said valves, and a float in one of said tanks operatively connected with said lever, said valves being adapted to alternately open and close the respective air inlet and suction passageways of each of said tanks.
23. In a liquid feeding device, the combination with a liquid supply source and an aspirator, of a liquid receiving tank connected with said supply source, a second tank connected with said supply source, each of said tanks being provided with an air inlet passageway, a suction conduit connected with said aspirator and having divided passageways leading to each of said tanks, an oscillatory member having a pair of spaced recesses formed therein adapted to alternately register with said air inlet 95 passageways to open and close the same, a third recess in said oscillatory member arranged to alternately register with said divided passageways, an arm for actuating said oscillatory member, and a float in one 100 of said tanks operatively connected with said arm whereby the oscillatory member is moved to simultaneously effect the opening of the air inlet passageway leading to one of the tanks and a suction passageway leading to the other.
24. In a liquid feeding system, the combination with a liquid supply source and an aspirator, of a tank connected with said supply source and provided with an air inlet 105 passageway, a conduit connecting said tank with said aspirator, a valve adapted to alternately open and close said air inlet passageway and said conduit, a lever for actuating said valve, a float guide mounted in said tank having a longitudinal recess formed therein and a transverse slot intersecting said recess, a rod connected with said 110
- 120
- 125

lever and projecting into said recess, a pin connected with said rod and adapted to extend through said slot, a pivoted arm engaging said pin, a spring of greater length than the arm extending longitudinally thereof and having one end connected with the pin and the other anchored upon the tank, and a

float slidably mounted upon said guide and adapted to actuate said arm at predetermined points of travel upon said guide. 10

In testimony whereof, I affix my signature.

CLARENCE B. DES JARDINS.
